UNITED STATES PATENT OFFICE.

JAMES A. BALL, OF THORNTOWN, INDIANA.

HAY-STACKER.

SPECIFICATION forming part of Letters Patent No. 315,109, dated April 7, 1885

Application filed February 16, 1885. (No model.)

To all whom it may concern:

Be it known that I, JAMES A. BALL, a citizen of the United States, residing at Thorntown, in the county of Boone and State of Indiana, have invented a new and useful Improvement in Hay-Stackers, of which the following is a specification.

My invention relates to an improved device for loading and stacking hay.

10 The objects of my improvements are, first, to raise the hay by means of a short lever, and to afterward extend said lever, with its load, over the stack; second, to provide means for quickly folding the machine into compact form 15 for moving from place to place.

The accompanying drawings illustrate my invention.

Figure 1 is a view in perspective of the complete stacker. Fig. 2 is a plan as seen from 20 the line 2, Fig. 1. Fig. 3 is a partial section at the line 3, Fig. 2. Fig. 4 is a transverse section at 4. Fig. 5 is a similar section at 5, looking toward the end of the boom.

A is a rectangular bed-frame, two sides of 25 which form runners to facilitate its being drawn over a field; or it may be mounted on wheels. On the central cross-timber of the bed-frame is erected a mast, B, which has a base-plate, b, which is hinged at c to the cross-timber. A collar, d, is secured to the mast, and the mast is braced by stay-rods e, which are hinged to the four corners of the frame A and hook into suitable eyes formed in said collar, the purpose being to permit the folding down of the mast upon the bed-frame.

Resting upon collar d is a loosely-fitting sleeve, C, having at its lower end, on opposite sides, clevises f and g. An extensible boom is pivoted to clevis f. Said boom is made, 40 principally, of iron tubing, and consists of a pair of side bars, h h, connected at the ends by suitable castings, so as to leave a space between the bars and a central bar, i, adapted to slide longitudinally between and upon said side bars. A cross-head, j, is attached to the inner end of bar i, having friction-rollers k k, which engage the under side of bars h h. Bar i rests upon a friction-roller, l, mounted in the casting connecting the outer ends of bars h. A bell-crank hook, m, is pivoted to the cross-head j. Said hook engages a rod, n, secured

in the side bars, h, and is released by the operator pulling on a line, o, attached to the opposite end of the hook. The hoisting-rope p is attached to cross-head j, and passes from 55 thence outward over a pulley, r, which is attached to the outer end of the side bars. The rope then passes upward over a pulley, s, suspended from the swivel-head t, and downward to a snatch-block, u.

Pivoted to the upper end of sleeve C is a curved bar, v, having notches which engage rod n, for the purpose of sustaining the boom independently of the hoisting-rope.

D is a light spar pivoted to the clevis g, and 60 carrying the counterpoise w, which is raised sufficiently to pass over the draft-rope by a rope, x, passing from the end of the spar over pulley y to the windlass z.

The operation of my machine is as follows: 70 A hay-fork or other means for holding a mass of hay is attached to the outer end of bar i and loaded with hay. Power being applied to the hoisting-rope, bar i is prevented from drawing outward by hook m engaging rod n, and the 75 free end of the boom is consequently raised, with its load, until a sufficient height has been attained, the load being lifted with comparative ease, because of the shortness of the boom. Bar v is now drawn forward into engagement 80 with rod n, thereby holding the boom against further upward or downward movement. The load being balanced by the counterpoise w, the boom, with its load, is easily rotated about the mast to bring the load opposite any desired point. Hook m is now released from its engagement with bar n, and a further draft on the hoisting-rope slides bar i outward until the load is over the stack or other place where it is desired to deposit it. The load having 90 been discharged, a relaxation of the draft-rope allows bar i to slide inward, the boom being held up meanwhile by ratchet-bar v until said bar is struck by the cross-head j, thereby disengaging it from rod n and permitting the descent of the boom.

To prepare the machine for removal, counterpoise w is removed, the boom and the counterpoise-spar are drawn up close to the mast, and stay-rods e are disengaged. The mast is 100 then folded down upon the bed-frame.

As an additional security to the mast when

raised, a bolt, *q*, may be passed through lugs secured to the bed-frame and across the free end of base-plate *b*.

I claim as my invention—

- 5 1. The combination, in a hay-stacker, of a bed-frame, a mast erected upon the bed-frame, a sleeve adapted to rotate about said mast, a boom consisting of a fixed part hinged to said sleeve, and an extensible part adapted to slide along said fixed part, a pulley secured to the free end of said fixed part, a second pulley mounted upon the mast-head, a draft-rope secured to the inner end of the extensible part of the boom and passing over said pulleys, and 15 means for detachably connecting the extensible part of the boom with the fixed part, whereby the boom is first raised by the draft-rope and afterward extended thereby, substantially as specified.
- 20 2. In a hay-stacker, the extensible boom consisting of a fixed part composed of two parallel bars united at their ends and having a space between them, a third bar arranged to slide between said parallel bars and having a 25 cross-head engaging said bars, and a hook pivoted to said sliding part and adapted to engage said fixed part, all combined substantially as and for the purpose specified.

3. In a hay-stacker, the combination of a bed-frame, a mast erected on said frame, a 30 sleeve adapted to rotate about the mast, an extensible boom hinged to the sleeve, a spar hinged also to the sleeve opposite the boom, a counterpoise-weight attached to said spar, and 35 ropes and pulleys for raising said boom and spar, all substantially as specified.

4. The combination, with the mast, the sleeve thereon, and the boom hinged to said sleeve, of the ratchet-bar pivoted to the sleeve and adapted to engage the boom, substantially 40 as and for the purpose specified.

5. The combination, in a hay-stacker, of the bed-frame, the mast hinged thereto, the collar secured to the mast, the stay-rods attached to the corners of said bed-frame and detachably 45 connected with the collar, the sleeve adapted to rotate on the mast, and a boom hinged to said sleeve, all substantially as and for the purpose specified.

JAMES A. BALL.
